(57) **CLAIM**

The ornamental design for forensic camera with multispectral imaging system, as shown and described.

DESCRIPTION

1. Forensic camera with multispectral imaging system

1.1 : Perspective

1.2 : Front

1.3 : Back

1.4 : Top

1.5 : Bottom

1.6 : Left

1.7 : Right

Design 1: Polarized UVA—VISIBLE—IR Camera with multispectral light groups used during Sexual Assault Forensic Examination.
